UNITED STATES PATENT OFFICE.

JOSEPH P. CONNELL, OF JERSEY CITY, NEW JERSEY, ASSIGNOR TO MANHATTAN
BRIAR PIPE COMPANY, OF BROOKLYN, NEW YORK, A CORPORATION OF NEW
YORK.

LABEL.

1,406,541.

Specification of Letters Patent. Patented Feb. 14, 1922.

Application filed October 4, 1921. Serial No. 505,312.

To all whom it may concern:

Be it known that I, JOSEPH P. CONNELL, a citizen of the United States, and resident of Jersey City, in the county of Hudson and State of New Jersey, have invented certain new and useful Improvements in Labels, of which the following is a specification.

This invention relates to labels and more particularly to labels intended for use in connection with smoking pipes; and has special reference to the provision of a label suitable for cartons or boxes in which may be packed any of a variety of styles or shapes of smoking pipes, the label being adapted for designating the characteristics of a particular style of pipe or pipes contained in any given box or carton.

In the sale and handling of smoking pipes considerable difficulty is experienced by the trade in properly identifying and quickly determining the characteristics of the pipes as regards their style, make or price. Smoking pipes are manufactured in a variety of styles, forms or shapes and are packed and distributed in containers or cartons, each style or shape of pipe having parts made from differing materials, the bits being made, for example, from such a variety of materials as rubber, horn, celluloid, amber or bakelite. The varying factors of style, make and material and the resulting varying factor of price of the pipe are sources of constant confusion to the distributing and retailing trade, difficulties being constantly experienced in properly identifying and quickly ascertaining the exact type or types of pipes packed in a given container and in rapidly selecting the particular style and make of pipe demanded by a purchaser. It

has therefore been found desirable to provide a form of label universally adapted for or suited to containers in which may be packed any one or more of the numerous styles and makes of pipes, the labels bearing representations by which the characteristics of the pipes packed in a given carton may be fully ascertainable from a quick inspection of the label attached to the container, and a prime desideratum of my invention relates to the provision of such a label.

One of the causes or reasons for the confusion hitherto existing in the distributing and retail trade lies in the fact that numerous distributors and retailers are unaware of and generally unacquainted with the dif-

ferent styles of pipes marketed and the different technical as well as trade names by which the pipes are known and sold. In order to eliminate this cause for confusion it has been found desirable and my present invention aims to provide a label in which the various styles or shapes of the pipes manufactured and marketed may be illustrated on the label for ready inspection, the particular style or styles of pipes packed in a given container being designated and visibly associated with the technical name or names of the designated pipes, this leading to a ready identification of the style of the pipe in the container not only, but resulting in instructing and acquainting the trade by constant association of style and name of the technical names by which pipes are known and sold.

The principal objects of my invention may therefore be said to include, besides the provision of a label adapted or suited for containers holding any of different types of articles such as smoking pipes, the provision of a label in which the particular style or shape of a variety of styles of pipes and the name of the style of pipes packed in a given container may be quickly ascertainable from a rapid inspection of the label; the further provision of a label in which the price of the article may be designated in a novel manner on the label and in which other facts and characteristics such as the make of the pipe and the number of pipes contained in a carton may be readily indicated and the general provision of a label adapted for a large variety of articles such as pipes which shall at once be instructive and helpful to the trade and neat and attractive in appearance.

To the accomplishment of the foregoing and such other objects as many hereinafter appear, my invention consists in the elements and their relation one to the other, as hereinafter particularly described, and sought to be defined in the claims, reference being had to the accompanying drawings which show a preferred embodiment of my invention, and in which:

Figures 1 and 2 are views of the label showing two of a variety of uses to which the label may be put.

As hereinbefore referred to, smoking pipes are packaged in bulk in containers and so sold to the trade, any given package containing any one or a plurality of a variety of

styles and makes of pipes. As pointed out, a desideratum of my present invention is to acquaint the trade with the various styles or shapes of pipes manufactured and marketed and to supply means for readily indicating to a dealer the type or style and make of the pipe packaged in any particular carton or box. To this end I provide a label comprising a label body 10 made of the usual sheet material and I provide a series of pictorial representations 11, preferably imprinted on the label body 10, the pictorial representations 11 portraying or illustrating the various styles or shapes of pipes made and marketed by the manufacturer. In the label shown in Figure 1 of the drawings, 12 styles of pipes are illustrated, the pictorial representations 11 being spacedly arranged on the label to make a neat and attractive label dress. This design of label not only serves to inform the distributor and retailer of all the styles of pipes manufactured, but the label serves and is suited for packages or containers holding pipes of any particular style, the label therefore being of universal utility as applied to smoking pipes. The label is attached in the usual way to the carton or box containing the pipes and for the purpose of readily indicating to the dealer the particular style or styles of smoking pipes contained in any particular carton, the pictorial representation of the particular style packed in a carton is marked in any desired manner with differentiating indicia. Thus, if the carton is to contain the style corresponding to the pictorial representation 12, such pictorial representation is marked as with a star 13 or other suitable indicia on or within the outline of the pictorial representation 12. It is further desired, as hereinbefore referred to, to generally acquaint and instruct the dealers as to the technical name of the pipes marketed and of the particular style or styles contained in a given carton. To this end I provide the label preferably with a space 14 adjacent one of the corners thereof, in which space is inscribed a descriptive representation of the particular style or styles contained in the given carton. Thus, if the carton should contain the style or shape of pipe known to the trade as the "Poker", the word "Poker" will be inscribed or imprinted as at 15 in the said space 14. For further indicating the fact that the pictorial representation 12 and the descriptive representation 15 correspond, the space 14 may be supplied with indicia such as a star 16 corresponding to the star 13 within the outline of the pictorial representation 12. In this manner the dealer is at once advised of the name as well as the style of the pipes in a container, enabling him to handle the article in a more intelligent manner, in addition to enabling him to accu-

ately and rapidly select a style of pipe called for by the purchaser.

For the purpose of indicating quantity or the number of pipes that may be packaged in a carton, I provide a second space 17 located preferably at another corner of the label, and on the said space is imprinted the word "Quantity", as shown at 18. Below the term or word "Quantity" may be inscribed or imprinted the number of pipes 75 held in a carton, the label in Figure 1 being supplied with the numeral 100 designated as 19 to indicate that that number of pipes is packaged in the particular carton to which this label is attached. 80

It is further desired to provide the dealer with a ready means for informing him of the make of the pipe such, for example, as whether the bit is ring mounted or flush mounted, or whether it is made out of rubber, horn, celluloid, amber, bakelite or other material, and to this end I provide the label at the remaining corners thereof with one or more spaces 20 and 21 respectively, the said spaces being intended for an inscription of the trade number and trade name of the particular style of pipe packaged in a carton, the said trade name or trade number being a key as to whether the pipe is ring or flush mounted, or whether it is made with a rubber bit, horn bit, etc., as well as denoting whether the pipe is finished natural, Italian or otherwise. 90

The pipes, due to the variety of styles and makes of manufacture, have different selling prices and to the end of supplying means for quickly designating in code the price of the pipes, I provide the label preferably with a central space 22 having preferably a circular cross sectional area, the said space having any selected colored background, the selected color designating or denoting the price. Thus, for instance, a yellow background in the space 22 would denote a 25¢ pipe; blue a 50¢ pipe; red, a \$1.00 pipe; green, a \$1.25 pipe, etc. In Figure 1 of the drawings the central space 22 is designated as blue, the label shown in Figure 1 being thus adapted for a container holding 50¢ pipes. In the said space 22 may be imprinted or impressed the trade mark of the manufacturing concern, such trade mark being indicated at 23. 115

The label may be further provided with an advertising space for the manufacturing concern and to this end I provide the label with an elongated space 24 at the bottom thereof, in which is imprinted the name or style of the manufacturer as, for example, "John Doe Pipe Co.", shown in Figure 1. The space 24 may also be supplied with a colored background corresponding to the colored background in the space 22, this for the purpose of obtaining a neat and attractive label. 120 125 130

In Figure 2 of the drawings I show my novel label as applied to a container holding pipes having different characteristics than the pipes for which the label in Figure 1 is intended. The label in Figure 2 is intended for attachment to a container in which an assortment of all the makes of pipes are packaged and to this end in the space 14 of the said label the word "Assorted" as designated at 25 may be inserted. The other spaces on the label may be provided with indicia or legends designating different facts and characteristics of the pipes packaged in this carton, the quantity space 17 designating, for example, that 50 instead of 100 pipes are packaged in the container, the price space 22' indicating to the dealer that the price of the assorted pipes contained in the carton corresponds to the color green, and therefore amounts to \$1.25. The spaces 20 and 21 may further be suitably inscribed in noting the particular make and construction of the pipes.

The manner of making and using my novel label will, in the main, be apparent from the above detailed description thereof. It will be further apparent that I have provided a label suited to containers or cartons holding any of a variety of styles or shapes of pipes, in which the various styles or shapes will be portrayed or illustrated on the label for the benefit of the dealer, and in which the style as well as the technical name of any particular style or styles of pipes in a given container will be indicated to the dealer and perceptible at a glance from inspection of the label. It will be further apparent that the label provides a ready means for denoting other facts and characteristics of the pipes, such as quantity, make and price, and that all the representations on the label are so coordinated as to provide a label having the data neatly and instructively arranged, the whole presenting an attractive dress for pipe containers.

While I have shown my device in the preferred form, it will be obvious that many changes and modifications may be made in the structure disclosed without departing from the spirit of the invention, defined in the following claims.

I claim:

1. A label adapted for designating the style or styles of articles contained in a carton or box comprising a label body bearing pictorial representations of different styles or shapes of the articles marketed and having a designated identifying space adapted for bearing a descriptive representation of the particular style or styles of articles contained in a given carton.

2. A label adapted for designating the style or styles of smoking pipes contained in a carton or box comprising a label body

bearing pictorial representations of a variety of styles or shapes of pipes marketed and having a defined identifying space bearing a descriptive representation designating the particular style or styles of pipes contained in a given carton. 70

3. A label adapted for designating the style or styles of articles contained in a carton or box comprising a label body bearing pictorial representations of different styles or shapes of the articles marketed and having a designated identifying space bearing a descriptive representation of the particular style or styles of articles contained in a given carton, the identifying space and a 80 pictorial representation of the style of article in the carton being provided with corresponding indicia whereby the name and style of the article in the carton will be perceptible from an inspection of the label. 85

4. A label adapted for designating the style or styles of smoking pipes contained in a carton or box comprising a label body bearing pictorial representations of different styles or shapes of pipes marketed and means on said label body for designating the style or styles of pipes contained in a given carton. 90

5. A label adapted for designating the style or styles of articles contained in a carton or box comprising a label body bearing pictorial representations of different styles or shapes of the articles marketed and having a designated identifying space adapted for bearing a descriptive representation of the particular style or styles of articles contained in a given carton, the label body being further provided with additional defined spaces provided for denoting the quantity, trade number and trade name of the 100 articles in the said carton. 105

6. A label adapted for designating the price and style of articles contained in a carton or box comprising a label body bearing a space having a selected colored background intended for denoting the price of the articles in the box, the label body being provided with pictorial representations of different styles or shapes of the articles as marketed and being further provided with 115 a designated identifying space provided for bearing a descriptive representation of the particular style or styles of articles contained in a given carton. 110

7. A label adapted for designating the 120 differentiating characteristics of articles contained in a carton or box comprising a label body provided with a central trade mark space having a selected colored background intended for denoting the price of the articles in the box, a plurality of pictorial representations of different styles or shapes of the articles marketed, said representations being arranged about the said central trade mark space and a plurality of 125 130

defined spaces located in the corners of the label, one of these spaces being provided for bearing a descriptive representation of the particular style or styles of articles contained in a given carton.

8. A label adapted for designating the differentiating characteristics of articles contained in a carton or box comprising a label body provided with a central trade mark space having a selected colored background intended for denoting the price of the articles in the box, a plurality of pictorial representations of different styles or shapes of the articles marketed, said representations being arranged about the said central trade mark space and a plurality of defined spaces located in the corners of the label, one of these spaces being provided for bearing a descriptive representation of the particular style or styles of articles contained in a given carton, the other of the spaces being provided for bearing legendary matter denoting the quantity, trade name and trade number of the articles in such carton.

9. A label adapted for designating the style or styles of articles contained in a carton or box comprising a label body bearing pictorial representations of different styles or shapes of the articles marketed and means on said label body for designating the name and style of the article contained in a given carton.

10. A label adapted for designating the differentiating characteristics of articles contained in a carton or box comprising a label body provided with a central space having a selected colored background intended for denoting the price of the articles in the box, a plurality of pictorial representations arranged about the said central space, the pictorial representations designating different styles or shapes of the articles marketed and means on the said label for identifying the style or styles of articles contained in the said carton.

Signed at New York, N. Y., in the county of New York and State of New York, this 30th day of Sept. A. D. 1921.

JOSEPH P. CONNELL.
